UNITED STATES PATENT OFFICE.

JOHN T. THOMPSON, OF NEWPORT, KENTUCKY.

MEANS FOR LUBRICATING AMMUNITION.

1,305,028.

Specification of Letters Patent. Patented May 27, 1919.

Original application filed June 16, 1917, Serial No. 175,152. Divided and this application filed October 16, 1917. Serial No. 196,883.

To all whom it may concern:

Be it known that I, JOHN T. THOMPSON, a citizen of the United States of America, and resident of Newport, in the county of Campbell and State of Kentucky, have invented new and useful Improvements in Means for Lubricating Ammunition, of which the following is a specification.

The present invention relates to ordnance, 10 this application being a division of my former application Sr. No. 175,152, filed June 16, 1917. More particularly the invention relates to means for effecting lubrication between the contacting surfaces of the case of 15 a cartridge, shell, or other type of fixed ammunition, and the chamber of the gun or fire arm containing the ammunition, preferably by lubricating the case of a cartridge, shell or other type of fixed ammunition before 20 it is seated in the chamber.

The object of the present invention is to provide means for obtaining proper lubrication between the contacting surfaces of the ammunition case and the firing chamber of 25 the gun or firearm, so as to reduce and make more uniform and constant the frictional resistance between the contacting surfaces, and thus facilitate the extraction of the ammunition case from the chamber and 30 improve the operation of the firing device.

More particularly is it the object of my invention to provide a gun or firearm, or the mechanism for automatically feeding the ammunition thereto, during operation of the 35 gun or firearm, with lubricating means so disposed with respect to the firing chamber as to effect proper lubrication of the contacting surfaces between the ammunition case and the firing chamber. In the preferred forms shown and described in the 40 present illustrated disclosure of my invention, the lubricant is applied to the ammunition while the latter is passing into the magazine or from the magazine to the firing chamber, or both; but, of course, the desired 45 lubrication may be secured in various other ways, it being only essential that the ammunition be lubricated by means associated with the gun, or firearm, or the means for feeding the ammunition to the firing chamber, or that lubrication be effected during or 50 after its introduction to the gun mechanism.

To this end the present invention more particularly involves the use of rotatable 55 lubricating pads and lubricating pads having convex surfaces. In the preferred em-

bodiment of the invention herein illustrated the lubricating pads are both convex and rotatable.

In the drawings herewith, and in the description accompanying those drawings, the invention is shown as applied to a magazine rifle of any ordinary or desired construction; the ammunition is shown as a cartridge made up of a charged metallic case or shell 60 with a bullet mounted therein in the usual manner, and the lubricating means is shown as comprising a pad or a series of pads to which the lubricant has been applied, and with which the ammunition is brought into 65 contact while the latter is passing into the magazine or from the magazine to the firing chamber, or both, but it is to be understood that this illustration and description is merely one adaptation of the invention and 70 is in no way restrictive of the invention.

In the drawings:

Figure 1 is a longitudinal sectional view through so much of a magazine rifle as is necessary to show the application of one embodiment of my invention thereto, in this embodiment the lubricating pads being disposed within and extending longitudinally 80 of the magazine opening of the receiver.

Fig. 2 is a vertical sectional view taken 85 transversely through the receiver and magazine of a gun structure similar to that shown in Fig. 1.

Fig. 3 is an enlarged detail view taken on a longitudinal line through the magazine 90 opening of the gun shown in Fig. 2.

Fig. 4 is a sectional view through a lubricating pad of the preferred form to which the present application is directed.

Fig. 5 is a sectional view taken transversely through the receiver showing the lubricating pad mounted upon the inclined surface over which the cartridges ride as they are advanced into the firing chamber.

Fig. 6 is a longitudinal view taken centrally through Fig. 5.

Fig. 7 is a transverse vertical sectional view through the magazine portion of another type of gun, and shows another embodiment of my invention.

Fig. 8 is a sectional view taken on the line 8—8, Fig. 7; and

Fig. 9 is a vertical longitudinal view through the structure shown in Fig. 7.

Referring to the drawings, and more particularly to Fig. 1, wherein is disclosed so much of a regulation rifle now used in the

United States Army as is necessary to illustrate the application of my invention there-to, 10 designates the stock, 11 the barrel, 12 the breech bolt, 13 the firing pin rod, 14 the 5 striker, 15 the firing chamber of the barrel, and 16 the magazine. Located within the magazine is a follower 17, and the magazine is closed by a floor plate 18. The follower plate is normally urged upwardly so as to to retain the uppermost cartridge 20 against the overhanging ledge 21, (Fig. 2) by means of a magazine spring 21^a. Between the magazine and the barrel is a receiver 22 having a slanting or inclined feeding surface 23, which directs the cartridges, during the feeding of the same from the magazine to the firing chamber, into the firing chamber. It is not deemed necessary to describe each of the parts illustrated, for the construction of these parts and the operation of the gun or rifle will be readily understood by those familiar with this art. It is understood, of course, that during the operation of the gun and upon extraction of the empty ammunition case, the bolt 12 is withdrawn from the magazine opening and the follower urges the uppermost shell upwardly against one of the overhanging ledges 21. Upon the forward movement of the bolt, its forward end will engage the uppermost edge of the cartridge and force the same forwardly, and the cartridge will ride up the inclined feeding surface 23 into the firing chamber.

In the embodiments of my invention disclosed in Figs. 1 to 3, the lubricating means is shown as comprising pads 24 located in the magazine opening of the receiver 22 immediately above the upper edge of the magazine 16. These pads may be mounted in any suitable manner, but by way of illustration, they are disclosed as being located in grooves 25 extending longitudinally of the magazine opening of receiver 22, and these grooves have their opposite edges undercut so that the edges of the pads may engage in the undercut portions of the grooves, and be retained in position thereby.

The pads may be of any suitable material, and if desired, they may be constructed of any absorbent felt or fabric. For the purpose of introducing a lubricant to the pads I have disclosed oil holes 26 extending through the stock of the gun and the metallic walls of the magazine opening, and, of course, one or more of these oil ducts may be employed for each pad.

It will be seen that during the operation of the gun and while the cartridge is being loaded into the magazine or is passing from the magazine to the firing chamber, the cartridges are successively brought into engagement with one of the pads 24 so that the cartridges are delivered to the firing chamber in a lubricated condition. The pads

are located in the path of travel of the cartridges to the firing chamber so that proper lubrication of each cartridge is insured. When employing a magazine the lubricating means should be so positioned that each of the cartridges is brought into operative relation to the lubricating means in transit to the firing chamber. The cartridges are fed into the magazine 16 through the magazine opening of the receiver 22, and while being so introduced they come into contact with the lubricating pads 24. I have found that it is not necessary to lubricate the entire circumferential external surface of the cartridges or ammunition, and that it is only necessary to apply the lubricant to the cartridge along one or more lines of its periphery. The amount of lubricant necessary between the external surface of the ammunition and the internal surface of the firing chamber to insure a smooth operation of the gun, is comparatively small, the amount depending, of course, upon the type of gun used.

In Figs. 5 and 6, instead of locating the pads adjacent the upper edge of the magazine 16, I have illustrated a pad 24^b mounted upon the inclined surface 23 up which the cartridges ride when being fed into the firing chamber 15. It will be seen that as the cartridges ride up the inclined surface, they will wipe against the pad so as to take up a proper amount of lubricant.

In Figs. 8 and 9, I have shown my invention applied to a different type of magazine, 100 the cartridges being arranged in a single column instead of staggered as in Fig. 2, the arrangement being employed in the Ross rifle. The magazine is designated by the numeral 27 and adjacent the upper edge of 105 this magazine are located pads 24^c, these pads being similar in structure, and being mounted in a manner like those shown in Figs. 1 to 3.

In Fig. 4 I have shown by way of example, a preferred method of forming and mounting the lubricating pads in the gun. The pad 33 is cylindrical and is mounted to rotate about its axis. While I have illustrated the roller pad 33 as being mounted in 110 the side of the receiver in the same location as in Figs. 1 and 2, it is to be understood that the lubricating pads of the present invention may be rotatably mounted in either of the positions illustrated in the drawings 115 120 or in other suitable position.

When the pad is rotatably mounted and disposed transversely to the path of the cartridges, as shown in Fig. 4, the cartridges cause the pad to rotate as they pass thereby, 125 and owing to the frictional contact between the cartridges and the pad, the cartridges will also tend to roll over the pad. This rotation of either the pad or the cartridges or both, will cause the lubricant on 130

the pad to be distributed over the surface of the cartridges in a highly efficient manner. Moreover, the resistance offered by the pad to the passage of cartridges is reduced by 5 mounting the pad rotatably. The convex character of the projecting portion of the pad also permits the ready passage of the cartridges.

It will be noted that in each of the embodiments of my invention hereinbefore described the cartridges or ammunition are lubricated after or during their introduction to the gun mechanism, or both. During the movement of the cartridges into, or from the 10 magazine to the firing chamber, the cartridges engage against the lubricating means which are placed in their path so that the cartridges are suitably lubricated, and proper lubrication between the external surface of 15 each cartridge and the chamber is insured. However, the particular means and the manner for lubricating the cartridges are shown by way of illustration only; and it is understood that proper lubrication of the cartridges during or after their introduction to 20 the gun mechanism, or the means for feeding the cartridges thereto, may be considerably modified within the scope of the appended claims.

25 **I claim:**

- 30 1. A gun comprising a firing chamber, and having means movably mounted therein for lubricating ammunition before it is seated in the firing chamber.
- 35 2. A gun comprising a firing chamber, and having means rotatably mounted therein for lubricating ammunition before it is seated in the firing chamber.
- 40 3. A gun comprising a firing chamber, means for feeding ammunition to the firing chamber, and lubricating means rotatably

mounted along the path of travel of ammunition in transit to the firing chamber for lubricating the ammunition.

4. A gun comprising a firing chamber, 45 means for feeding ammunition to the firing chamber, and lubricating means rotatably mounted along the path of travel of ammunition in transit to the firing chamber for lubricating the ammunition, the lubricating 50 means being disposed transversely of the path of the ammunition so as to be rotated by the ammunition passing therealong.

5. A gun comprising a magazine, a firing chamber, means for feeding ammunition 55 from the magazine to the firing chamber, and a lubricant-carrying body rotatably mounted between any position of a cartridge in the holder and the firing chamber for lubricating the ammunition.

6. A gun comprising a magazine, a firing chamber, means for feeding ammunition from the magazine to the firing chamber, and a lubricant-absorbent body rotatably mounted between any position of a cartridge 65 in the holder and the firing chamber for lubricating the ammunition.

7. A gun comprising a firing chamber, means for feeding ammunition to the firing chamber, and convex lubricating means ex- 70 tending into the path of the ammunition so as to contact with the ammunition in transit to the firing chamber.

8. A gun comprising a firing chamber, 75 means for feeding ammunition to the firing chamber, and one or more convex lubricating pads extending into the path of the ammunition so as to contact with the ammunition in transit to the firing chamber.

Signed by me at Washington, D. C., this 80 tenth day of October, 1917.

JOHN T. THOMPSON.
